UNITED STATES PATENT OFFICE

2,308,248

BUILDING CONSTRUCTION

Maurice A. Rehn, Kansas City, Mo., assignor to
 Tramill-Rehn Lumber Company, Kansas City,
 Mo., a corporation of Missouri

Application August 12, 1940, Serial No. 352,227

5 Claims. (Cl. 20—4)

This invention relates to a building construction particularly adaptable to small cabins, roadside inns, and similar structures, and has for its principal object to provide prefabricated units which may be readily assembled at the site to form a building of the required size and shape.

Another object of the invention is to provide wall units that have finished exterior and interior sides formed of relatively thick tongue and grooved boards interposed by an insulating material, whereby the unit is self-supported without studs, and is weather-tight.

Other objects of the invention are to provide grooved headers engaging the upper ends of the inner and outer finish boards to assist in retaining the boards in assembly; and to provide window and door frames which are incorporated in the respective units, the frames having grooved exterior sides receiving the edges of the finish boards, similar to the grooved headers.

It is also an object of the invention to provide a unit wall or partition structure adapted to various interior and exterior designs, for example, the interior may consist of tongue and grooved knotty pine boards while the exterior may consist of ordinary tongue and grooved boards.

In accomplishing these and other objects of the invention, I have provided improved details of structure, the preferred forms of which are illustrated in the accompanying drawings, wherein:

Fig. 1 is a fragmentary perspective view of a portion of a building constructed in accordance with the present invention.

Fig. 2 is a horizontal section through one corner of the building.

Fig. 3 is a vertical section through a door of the building.

Fig. 4 is a similar section through a window of the building.

Fig. 5 is a similar section through an intermediate portion of the wall.

Fig. 6 is a horizontal section through a modified form of wall structure.

Referring more in detail to the drawings:

1 designates a building constructed in accordance with the present invention, and which preferably includes a plurality of prefabricated wall units 2. The units 2 may be of various size, that is, the unit may extend across the entire side of the building, or the side may be composed of a plurality of units joining with similarly fabricated corner units 3.

The units generally include a plurality of vertically arranged inner and outer boards 4 and 5, of suitable length to conform with the height of the

building walls and formed of a material of sufficient thickness so that the units are self-supporting without the use of studs usually employed in building construction. The edges of the boards 4 and 5 are preferably tongue and grooved as at 6—7 and 8—9 respectively, so as to provide interfitting joints arranged so that the joints between the inner boards are staggered with respect to the joints of the outer boards, as clearly shown in Fig. 2.

Interposed between the facing sides of the inner and outer boards, and clamped by the adjacent faces thereof, is a sheet of insulating material 10. The insulating material 10 may be of any suitable type, for example paper. The upper ends 11 and 12 of the inner and outer boards are in substantial registry and are received in grooves 13 of a header plate 14, which is preferably secured thereto by fastening devices, such as nails 15, driven through the plate and into the ends of the boards as shown in Fig. 5. The lower ends 16 and 17 of the boards are also in substantial registry and are nailed together and to a floor sill 18 having its lower edge substantially registered with the lower ends 16 and 17, the nails 19 being driven from the outer side through the respective layers of boards and into the sill as shown in Fig. 5.

Suitable openings may be provided in the units, for example a door opening 20 shown in Fig. 3. Inserted in the opening is a door frame 21 comprising side jambs 22 connected by a header jamb 23, having the outer faces thereof grooved as at 24 to receive the edges of the wall boards, the frame being secured by fastening devices such as nails 25 driven through the frame and into the boards. The door frame may include a stop 26 and a tread 27 for closing the space about a door 28 which may be of ordinary construction, the door being hinged to the frame as indicated at 29 and provided with a customary lock 30. Other of the units may be provided with window openings 31 carrying frames 32 corresponding to the door frames, and which carry sash 33 which may be secured to the sides of the frames by hinges 34 and retained in closed position by latches 35.

The corner units are formed of boards similar to the intermediate units, with the endmost boards 36 and 37 on one side lapping the edges 38 and 39 of the endmost boards of the other side and secured thereto by suitable fastening devices. In the corner units the insulating material 10 preferably extends continuously around the corner so that should the joint open up be-

cause of shrinkage, swelling, or the like, the insulation will maintain the seal.

Wall units of suitable number and having the required door and window openings may be provided and arranged upon a foundation or other suitable support 40, with the ends of the inner and outer wall boards and sills 18 resting on the support. The floor joists 41 may then be secured to the sills 18 and the flooring 42 laid upon the joists as in customary building practice. Since the boards comprising the inner and outer sides of the respective units have the joints overlapped, the adjacent sides of the respective units will therefore overlap so that they may be nailed together to form a continuous wall. A plate 43 is then preferably nailed on top of the header plates 14, after which the roof structure is applied, the rafters 44 thereof being notched to rest directly on the upper plates 43 as shown in Figs. 3 to 5 inclusive, filler blocks 44 being inserted between the respective rafters to enclose the space therebetween. The outer sheeting 45 is then applied to the rafters, followed by the roofing 46 as shown. The ceiling 47 may be affixed to the under side of the rafters and consist of any suitable material, such as wall board, veneer, or the like, to harmonize with the interior finish of the side walls. A quarter round 48 or the equivalent is nailed within the angle between the flooring and the walls as shown. The joint between the wall plates 14 and 43 may be covered by a frieze board 49 to complete the assembly.

If desired, the building may be provided with partitions 50 conforming in structure to the side walls, except that the boards 51 and 52 will correspond to the character of the inner boards of the side walls, and both the upper and lower ends thereof will be received in grooves 53 and 54 of head and base plates 55 and 56 respectively.

In the form of wall structure shown in Fig. 6, the inner and outer boards 57 and 58 may be of substantially the same thickness as the corresponding boards of the preferred form, but the edge joints may be in the form of shiplaps 59 and 60. In this construction the inner and outer boards preferably register with each other as shown in Fig. 6, with the sheet of insulating material 61 interposed therebetween, otherwise the structure is the same as that of the preferred form.

From the foregoing it is obvious that I have provided a building construction which is particularly adapted to small cabins and other inexpensive buildings, and that the buildings may be quickly and readily assembled from fabricated units at relatively small cost. It is also obvious that the wall and partition units are self-supporting and thoroughly insulated by the interposed sheet of insulating material. It is also obvious that the boards composing the wall unit are so jointed as to provide weather-tight joints. It is also obvious that the structure provides a building which is of strong, rigid construction, without the use of studding or other posts.

What I claim and desire to secure by Letters Patent is:

1. In a building construction, a wall unit including vertically positioned inner and outer boards arranged in face to face relation with the side edges of the inner and outer boards abutting each other and having the upper and lower end edges of both the inner and outer boards in registry, an insulating material interposed between said related faces of the inner and outer boards, a header plate having a groove receiving the

upper end edges of both inner and outer boards to retain said boards in assembly at the upper ends thereof, a sill extending transversely across the lower portion of the inner boards and with the lower edge thereof in substantial registry with the lower registering end edges of the inner and outer boards, and fastening devices extending through the inner and outer boards and into said sill for retaining the lower ends of said boards in assembly.

5 2. In a building construction, a wall unit including vertically positioned inner and outer boards arranged in face to face relation with the side edges of the inner boards in abutting contact with each other and staggered with respect to corresponding abutting edges of the outer boards and with the upper and lower end edges of both the inner and outer boards in registry, an insulating material interposed between said 15 related faces of the inner and outer boards, a header plate having a groove receiving the upper end edges of both inner and outer boards to retain said boards in assembly at the upper ends thereof, a sill extending transversely across the lower portion of the inner boards and with the lower edge thereof in substantial registry with the lower registering end edges of the inner and outer boards, and fastening devices extending through the inner and outer boards and into said 20 sill for retaining the lower ends of said boards in assembly.

25 3. In a building construction, a wall unit including vertically positioned inner and outer boards arranged in face to face relation and having interengaging tongue and groove vertical side edges, said inner and outer boards having the upper and lower end edges of both the inner and outer boards in registry, an insulating material interposed between said 30 related faces of the inner and outer boards with said faces of both inner and outer boards in contact with the insulating material, a header plate having a groove receiving the upper end edges of both inner and outer boards to retain said boards in assembly at the upper ends thereof, a sill extending transversely across the lower portion of the inner boards and with the lower edge thereof in substantial registry with the lower registering end edges of the inner and outer boards, and fastening 35 devices extending through the inner and outer boards and into said sill for retaining the lower ends of said boards in assembly.

4. In a building construction, a wall unit including vertically positioned inner and outer

40 boards arranged in face to face relation and having tongue and grooved joints at the vertical side edges of said boards, the joints between the juxtaposed inner boards being staggered with respect to the joints between the juxtaposed outer 45 boards and with the upper and lower end edges of both the inner and outer boards in registry, an insulating material interposed between said related faces of the inner and outer boards, a header plate having a groove receiving the upper end edges of both inner and outer boards to retain 50 said boards in assembly at the upper ends thereof, a second header plate nailed to the upper face of the grooved header plate, a sill extending transversely across the lower portion of the inner boards and with the lower edge thereof in substantial registry with the lower registering end edges of the inner and outer boards, fastening devices extending through the inner and outer 55 boards and into said sill for retaining the lower ends of said boards in assembly.

5. In a building construction, a wall unit including vertically positioned inner and outer boards arranged in face to face relation and having tongue and grooved joints at the vertical side edges of said boards, the joints between the juxtaposed inner boards being staggered with respect to the joints between the juxtaposed outer 60 boards and with the upper and lower end edges of both the inner and outer boards in registry, an insulating material interposed between said related faces of the inner and outer boards, a header plate having a groove receiving the upper end edges of both inner and outer boards to retain said boards in assembly at the upper ends thereof, a second header plate nailed to the upper face of the grooved header plate, a sill extending transversely across the lower portion of the inner boards and with the lower edge thereof in substantial registry with the lower registering end edges of the inner and outer boards, fastening devices extending through the inner and outer 65 boards and into said sill for retaining the lower ends of said boards in assembly.

6. In a building construction, a wall unit including vertically positioned inner and outer boards arranged in face to face relation and having tongue and grooved joints at the vertical side edges of said boards, the joints between the juxtaposed inner boards being staggered with respect to the joints between the juxtaposed outer 70 boards and with the upper and lower end edges of both the inner and outer boards in registry, an insulating material interposed between said related faces of the inner and outer boards, a header plate having a groove receiving the upper end edges of both inner and outer boards to retain said boards in assembly at the upper ends thereof, a second header plate nailed to the upper face of the grooved header plate, a sill extending transversely across the lower portion of the inner boards and with the lower edge thereof in substantial registry with the lower registering end edges of the inner and outer boards, fastening devices extending through the inner and outer 75 boards and into said sill for retaining the lower ends of said boards in assembly.

ends of said boards in assembly, and a floor having marginal support on said sill.

5. In a building, a corner wall construction including angularly extending panel-like units each consisting of vertically positioned inner and outer boards arranged in face to face relation with the vertical edges of the inner and outer boards in abutting engagement and having registering upper and lower ends, an insulating material retained in face to face contact with said related faces of the inner and outer boards, header members having longitudinal grooves for re-

ceiving the registering upper ends of the inner and outer boards, and sills extending across the lower portions of the inner boards and having their lower edges extending in substantial alignment with the lower registering ends of the inner and outer boards, said inner boards at said corner having the vertical side edges inset from the corresponding side edges of the outer boards whereby the vertical edges of the inner boards are overlapped by the outer boards.

MAURICE A. REHN.
